United States Patent Office.

EDWARD H. ASHCROFT, OF LYNN, MASSACHUSETTS.

Letters Patent No. 70,389, dated November 5, 1867.

IMPROVEMENT IN CONDENSERS.

The Schedule referred to in these Letters Patent and making part of the same.

TO ALL WHOM IT MAY CONCERN:

Be it known that I, E. H. ASHCROFT, of the city of Lynn, in the county of Essex, in the State of Massachusetts, have invented a new and useful Improvement in Steam-Condensers, &c.; and I do hereby declare that the following is a full and exact description thereof, reference being had to the accompanying drawings, and to the letters of reference marked thereon.

The nature of my invention consists in a certain device, to be hereafter described, whereby the waste, or exhaust steam of an engine is readily condensed and utilized by being returned to a suitable vessel and used over again, a matter of not only economy, but for obvious reasons otherwise desirable.

To enable others skilled in the art to make and use my invention, I will proceed to describe its construction and operation. In the drawings—

Figure 1 represents an elevation of my machine,

Figure 2 a vertical central section of the same, and

Figure 3 a top view.

A represents an ordinary exhaust or waste-steam pipe, in which I place several perforated or showering-pans, B, which are fed with cold water, which is forced up the tube. This tube C is placed inside of another one, D, to prevent the water in C from being heated by the exhaust steam passing up A at its lower part. As the steam ascends A it is met by a shower of spray from the lower showering-pan. Should any pass it, the same will be met by a similar shower from the next upper pan, and so on, having as many as may be found necessary. The water to supply the showering-pans can be furnished from a reservoir located above them, or it can be supplied through pipe C by an ordinary force-pump. At the top of this pipe it follows around an elbow, e, which has one or more openings, a, through which the water empties into one or more divisions in supply-vessel E. I show three openings a, and three divisions b, c, and d. Each of these divisions or chambers has a hole, f, in its bottom, from which lead pipes e to the several showering-pans B, thus supplying them. The divisions in the supply-vessel E are not absolutely necessary.

The water supplied to the pans, issuing from the orifices in the same, falling in fine showers, and condensing the ascending waste steam, also returns with it to a tank, being caught and conducted off in any suitable way, not necessary to describe, and all can be used over again in the boiler or otherwise, and a large percentage is thus saved of the best kind of pure and soft water. The end of the exhaust escape pipe proper, which leads into the waste or conducting pipe A, may have a hood over it, or be made with a neck or elbow, so that the condensed steam or water cannot fall back into it. Any mechanical fitting is obvious by which to carry it off at the bottom of pipe A.

Having thus described my invention, what I claim as new, and desire to secure by Letters Patent of the United States, is—

The combination and arrangement of the waste pipe A, showering-pans B, reservoir E, and supply pipe C, operating in the manner substantially as shown and described, and for the purpose set forth.

E. H. ASHCROFT.
